UNITED STATES PATENT OFFICE.

ROBERT E. MIDDAGH AND CARL L. ANDERSON, OF MCGILL, NEVADA.

REFILLABLE ELECTRIC FUSE.

Application filed June 11, 1920. Serial No. 388,281.

To all whom it may concern:

Be it known that we, ROBERT E. MIDDAGH and CARL L. ANDERSON, citizens of the United States, residing at McGill, in the county of White Pine and State of Nevada, have invented certain new and useful Improvements in Refillable Electric Fuses, of which the following is a full, clear, and exact description.

10 This invention relates to refillable electric fuses, and more particularly to means for holding the fuse strip in the body portion of the fuse in such manner that ready access may be obtained thereto for the purpose of renewing the fuse when it burns out.

Among the objects of the invention is to provide a fuse of the character referred to which will be very rigid when assembled, may be disassembled for refilling readily and quickly, and wherein there is no chance for the molten parts of the fuse to lodge and block the operation of the fuse and there are no small parts, such as screws, nuts or washers to retard the ready manipulation of the fuse head.

20 The invention has further for its objects to provide a fuse of this character which will be simple and cheap of construction, and in which the contact will be maintained efficiently during the operation of the fuse.

Other objects and advantages of the invention will be apparent from the following description of a preferred construction, in connection with the accompanying drawings, illustrating the same.

In the drawings:

Figure 1 is a longitudinal vertical section of the fuse;

40 Figure 2 is a similar section of the fuse taken at right angles to the plane of section of Figure 1;

Figure 3 is a transverse section on the line 3-3 Figure 6, looking toward the left, and showing also the key member 18, which is located to the right of said section line;

45 Figure 4 is a transverse section on the line 4-4 of Figure 6;

Figure 5 is a right hand end view of the fuse with the cap in position;

50 Figure 6 is a detail view, in side elevation, of the right hand end of the fuse as illustrated in Figures 1 and 2;

Figure 7 is a view similar to Figure 6, of the left hand end of the fuse;

Figure 8 is a left hand end view of the fuse with the cap in position;

Figure 9 is a section on the line 9-9, Figure 7, looking toward the right;

Figure 10 is a section on the line 10-10, Figure 1, looking toward the left; and

Fig. 11 is a perspective view of the locking disk.

The device comprises a fuse strip 2, of fusible material whose terminals are connected, preferably, by bolts and nuts, 4 and 4 to the blades 5, 5. In this connection it is to be observed that while we have shown herein a fuse of the "knife blade" type, the invention, as to most of its parts, is equally applicable to a fuse of the "ferrule" type.

A disk 12, best shown in Figures 9 and 10, having integral or rigid therewith a circular projection or inner disk 12^a receives the forked ends of the terminal blade 5 at the left hand end of the fuse, and a smaller disk 12^b is rigid with the reverse side of the disk 12, and is embraced by the forked portions of the blade where it passes through the disks 12, 12^a, as shown in Figure 9.

The opposite, or right hand end of the fuse, as viewed in Figs. 1 and 2, is slightly differently constructed as to the means for connecting that end of the fuse link with the casing member 1. At such end, the blade 5 passes through a disk 17 which is circumferentially of a size to neatly fit within the bore of the thimble 3 at that end of the fuse body. Rigidly secured upon the outer side of the disk 17 is an elongated key member 18, upon which is a smaller disk 20, the parts 17, 18 and 20 receiving the forked terminals of the blade 5 and being rigid therewith.

The body of the fuse comprises a tube of nonconducting material 1 to each end of which is secured a thimble 3 composed of annular portions 6, 8, which are spaced apart to provide an intermediate annular groove 10. The annular portion 8, as best shown in Figure 3, is preferably provided at diametrically opposite points with recesses 7, 7, and also with oppositely arranged smaller recesses, 11, 11, the latter being arranged 90° apart from the recesses 7, 7, or in such position that a line connecting the center of the recesses 11, 11, will be at right angles to a line connecting the centers of the recesses 7, 7. Thimbles 3 are

secured by rivets or otherwise suitably in a rigid manner to the body portion 1 of the fuse, and these thimbles are constructed precisely alike at each end, so as to be interchangeable in their relation to the connecting means for detachably securing the fusible link in position. As shown in Figure 11, a disk 21, provided with a central elongated aperture 24, two diametrically arranged inwardly projecting lugs 22, 22, and two similarly arranged recesses 23, 23, serves as a locking device for use in detachably connecting the link at its right hand end to the thimble 3 at that end of the body of the fuse. The fuse ends are covered by caps 15 which have inwardly projecting, diametrically arranged lugs 16, 16, for entering recesses 7, 7, and 23, 23, in the thimbles and disk 21, for locking the parts of the fuse together. Each of the end caps is provided with an opening 24 at the center portion of its closed end of the shape best shown in Figures 5 and 8. Said opening comprises two curved portions 28, 28, concentric with and slightly larger than the disks 20, and other curved portions 30, 30, arranged 90° from the first named curved portions and providing clearance to permit rotation of the legs of the blade 5 through 25 the locking operation. The spaces between the peripheries of the disks 20 provided by the cut-out curving portions 30 terminate in diametrically disposed openings 25, 25, which are adapted to receive either of the 35 blades 5 in assembling the cap upon the end of the fuse.

To assemble the various parts of the fuse the link with the elements heretofore described as being rigidly secured thereto is inserted in the casing from the left hand end, as viewed in Figure 1, the disk 17 passing freely through the body and cap portions until the disk 12 has become seated upon the left hand end of the ferrule 3, the 40 lugs 14 entering the recesses 11. It will be noted that the recesses 13 in the disk 12 will register with the recesses 7 at the outer end of the thimble 3. The disk 21 is then slipped over the right hand end of the device, the blade 5 passing through the slot 24', and the lugs 22, 22, of the disk entering the recesses 11, 11, at the right hand end of the fuse, the opening 24' also fitting snugly about the elongated projection 18 thereat. The engagement of the lugs 22 of the disk 21 with the openings 11 at the right hand end, and the similar engagement between the lugs 14 and the recesses 11 at the left hand end, effectively lock the fuse 45 link and the blades carried thereby against rotation relatively to the body of the fuse. The end caps 15 are then placed over the blades at each end of the fuse, the blades passing through the openings 25 in the cap 50 until the latter is seated firmly against the disks 12 and 21. The cap is then rotated in a direction to move the curved portions 30 about the legs of the blades until such legs abut against shoulders at the terminations of the spaces between said curved portions and the beginning of the curves 28, 28, which are closely adjacent to the surface of the disk 20. The cap is thus firmly locked in position on the end of the fuse, but may be easily removed by rotating it 55 in a direction reversely to that described. When each cap is rotated in a direction to lock it to the end of the fuse the lugs 16, 16, pass out of registration with the slots 7, 13, and are positioned back of the 60 flange or ring 8, whereby the cap is prevented from being pulled off from the end of the fuse. The connection described is, in effect, a bayonet slot connection, but in lieu thereof there may be employed any other 65 suitable connection, the invention not being limited to the bayonet slot connection.

Changes may be made in other respects than that above referred to in the details of construction or in the relative arrangement of the various parts hereinafter referred to, without departing from the principles of the invention as embodied in the appended claims.

Having described the invention what is 70 claimed is:

1. A refillable cartridge fuse having, in combination, a body portion, thimbles secured to the ends of the body and constructed for interlocking engagement with 75 end caps, a fusible strip having at one end a terminal carrying a disk arranged to fit within the body and thimbles, having at its opposite end a disk of a size too large to enter the body with interlocking means to cooperate with the thimble in preventing relative rotation of the body and fusible link, and end caps for the body having means for co-operating with the thimbles to lock said caps in position.
2. A refillable cartridge fuse comprising, in combination, a hollow insulating body portion having thimbles secured at the ends thereof, a fusible strip connected to fuse terminals, one of said terminals carrying a disk of a size to enter the body of the fuse and pass from end to end thereof and the other terminal having a disk of a size larger than the bore of said body, interlocking means between the last named disk and one of said 85 thimbles to prevent relative rotation of the strip and body, and end caps provided with means for interlocking engagement with the thimbles at the ends of the fuse, said caps being constructed and arranged for rotation 90 to lock the caps to the thimbles.
3. In a refillable cartridge fuse, the combination with a hollow insulating body portion having at each end a thimble provided with two pairs of diametrically arranged 95

- recesses, and a circumferential groove back of said recesses, a fusible strip having at one end a terminal carrying a disk of a size to enter and pass freely from end to end of said tube and thimbles, said disk having a projection, said strip at the opposite end having a terminal carrying a disk of a size too large to pass within said body, and having diametrical lugs to cooperate with two recesses in the end of a thimble, a detachable locking disk for use at the opposite end of said body, and constructed with a central slot, diametrically arranged edge recesses, and diametrically arranged inwardly projecting lugs, said disk being arranged to fit over said projection on the small disk at the end of the fuse with the lugs of said disk interlockingly engaging two of the recesses in the thimble and the center slot engaging a projection at said end of the fuse to lock the same to the thimble, and end caps arranged to interlock with portions of said thimbles and to retain the link and connected parts within the body of the fuse.
4. In a refillable cartridge fuse, the combination with a hollow insulating body portion having at its ends thimbles each provided with diametrically arranged recesses located approximately 90° apart, a fusible strip having a terminal at one end carrying a disk of a size to freely enter and pass from end to end of said body and having an elongated projection on its outer face, a disk of larger size carried by a terminal at the opposite end of said strip, said disk having inwardly projecting lugs to enter and lockingly engage with corresponding recesses in the thimble at that end of the fuse, a locking disk having a central opening to engage the elongated projection at the first-named end of the strip, and having also inwardly projecting lugs to lockingly engage recesses in the thimble, and also recesses to align with other recesses in said thimble, and caps for the opposite ends of the fuse body provided with internal lugs to enter the recesses and interlockingly engage with the end thimbles upon rotation, and having openings at their ends provided with curved portions to cooperate with a terminal blade and elongated openings to permit said caps to be placed over the blades prior to their rotation in locking the caps to the fuse.
5. In a refillable cartridge fuse, the combination with a hollow insulating body portion having at its ends thimbles provided with circumferential grooves, and pairs of diametrically arranged recesses communicating with said grooves, a fusible strip having at one end a terminal carrying a disk of a size to freely enter said body portion and at its opposite end a terminal carrying a disk of larger size, the latter having lugs for locking engagement with two recesses in a thimble, blades projecting beyond said disks, a locking disk having lugs for engagement with the recesses of the thimble at the end of the fuse which is occupied by the disk first mentioned, and end caps having means for locking engagement with the circumferential grooves of the thimbles, and provided with openings in their ends formed by two pairs of curves of different radii to provide curved clearance passages for the blades when the caps are rotated, and elongated openings communicating with said passages to permit the caps to be slipped over the ends of said blades.
6. A refillable cartridge fuse comprising, in combination, a hollow insulating body portion having thimbles secured at the ends thereof, a fusible strip connected to fuse terminals, one of said terminals carrying a disk of a size to enter the body of the fuse and pass from end to end thereof and the other terminal having a disk of a size larger than the bore of said body, interlocking means between the last-named disk and one of said thimbles to prevent relative rotation of the strip and body, and end caps provided with means for rotative engagement with said thimbles to retain said disks against longitudinal movement.
- In testimony whereof we have hereunto set our hands this 2nd day of June A. D. 1920.
